UNITED STATES PATENT OFFICE.

OSCAR C. NELSON, OF WESTBROOK, MINNESOTA.

COMBINED CHAIR AND IRONING-TABLE.

1,170,664.

Specification of Letters Patent.

Patented Feb. 8, 1916.

Application filed February 26, 1915. Serial No. 10,775.

To all whom it may concern:

Be it known that I, OSCAR C. NELSON, a citizen of the United States, residing at Westbrook, in the county of Cottonwood and State of Minnesota, have invented certain new and useful Improvements in Combined Chairs and Ironing-Tables; and I do hereby declare the following to be a full, clear, and exact description of the invention, such as will enable others skilled in the art to which it appertains to make and use the same.

This invention relates to new and useful improvements in combined chair and ironing tables, and has for its principal object to provide an ironing table which may be easily and quickly folded into such a position as to provide a chair when so desired.

Another object of the invention is to provide a particularly simple and efficient device which may be easily and cheaply constructed of any suitable material and which will be light so as to render the same easily handled.

A further object of the invention is to provide a device which may be locked in either position to avoid danger of accidental folding of the device.

With these and other objects in view, the invention consists in the novel combination and arrangement of parts which will be fully set forth in the following specification and accompanying drawings, in which;

Figure 1 is a side view in elevation of a combination ironing table and chair constructed in accordance with this invention showing the device as it would appear when in use as a chair, Fig. 2 is a top plan view of Fig. 1, Fig. 3 is a bottom plan view of the device in use as an ironing table, and Fig. 4 is a longitudinal sectional view of the device as an ironing table.

Referring now to the drawings by characters of reference, the numeral 1 designates as an entirety the supporting structure which comprises a pair of frames, each of which is formed of the cross pieces 2 and 3 which are secured together intermediate their ends by means of the screw or bolt 4. These cross pieces are preferably notched out where they join to prevent the same from collapsing. Connecting the cross pieces 2 is the rod 5 which serves as a support for the seat when device is used as a chair. Each of the cross pieces 3 hereinbefore referred to is provided with an angular extension 6, the

upper face of which is curved as at 7, and this angular extension is provided with the arcuate slot 8, the use of which will appear hereinafter.

Pivottally mounted between the cross pieces 3 is the connecting bar 9 to which the arms 10 are secured. These arms 10 are arranged to swing with the bar 9 on its pivot and are connected at their upper ends by the bar 11 and the central portion of this bar 11 is reduced and secured through the bearing bracket 12 which is screwed or otherwise secured as at 13 to the portion of the device which forms the seat.

The seat portion of the device is designated generally by the numeral 14 and comprises the main body 15 having formed at one end the reduced portion 16, one wall of which is beveled as at 17 to fit the beveled recess 18 of the back portion designated generally by the numeral 19. This back portion 19 comprises the body 20 which is recessed at one end to form the ears 21, which ears overlie the lateral edges of the reduced portion 16 of the seat 14, and are pivoted thereto as at 22. Formed at the end of the body 20 opposite the ears 21 is the reduced extension 23 and this body 20 is provided with apertures in which the screw eyes 24 extend. These screw eyes are designed to extend through the slots 8 and lock the back in various adjusted positions when the device is in use.

In order to lock the back 19 and seat 14 in horizontal position as shown in Fig. 4 when the device is in use as an ironing board, there are provided the straps 25 which are designed to form retainers for the locking bolts 26, one end of which is enlarged as at 27, and the opposite end is designed to lie beneath the beveled edge 17 of the reduced portion 16 of the seat 14 to hold the under surface of the seat and the back flush, and thereby form a smooth joint on the upper side thereof.

In order that the cross pieces 2 and 3 may be further braced and so as to provide an arm for the chair, there are provided the arcuate connections 28 which are screwed or otherwise secured as at 29 to the cross pieces 2 and 3 and bridge the space between the upper ends thereof.

It will be apparent from the foregoing that in use when it is desired to use the device as a chair, the screw eyes 24 are loosened which will permit the back and seat, form-

ing the table of the ironing board, to slide rearwardly. This will cause the arms 10 to swing rearwardly and downwardly until they reach the position shown in Fig. 1, in which position the seat will be comparatively level and the back inclined upwardly and rearwardly therefrom. The screw eyes may then be tightened, and it will be apparent that the whole will be locked together 10 against accidental movement and the device may be used as a chair. Upon returning the device to its position as an ironing board, the screw eyes are again loosened and the seat and back lifted at their joint until they 15 form a level and smooth surface, at which time the seat is pulled forwardly, thus causing the arms 10 to swing on their pivots into the position shown in Fig. 4 thus forming a support under the seat portion of the ironing board and by placing the bolt 26 in the 20 position shown in Figs. 3 and 4, it will be apparent that the top of the ironing board will be smooth, thus presenting a surface over which the iron may freely travel. After 25 the board has been drawn to the farthest forward position the screw eyes are again tightened and it will be apparent that the whole will be supported rigidly and danger of accidental movement will be eliminated. 30 While in the foregoing there has been shown and described the preferred embodiment of this invention, it is to be understood that such changes may be made in the combination and arrangement of parts as will 35 fall within the spirit and scope of the invention as defined in the appended claims.

What is claimed is:

1. A combination ironing board and chair including a supporting structure comprising

ing cross pieces, rods connecting the cross pieces, and arms pivoted to the rods, a seat pivoted to the ends of the arms, a back pivoted to the seat, extensions on one set of cross pieces, screw eyes extending through the extensions and into the back, and means 40 to lock the seat and back in parallel relation.

2. A combination ironing board and chair including a supporting structure comprising cross pieces, rods connecting the cross pieces, extensions on one set of the cross pieces, said 50 extensions being provided with arcuate slots, pivoted arms secured to one of the rods, a seat, said arms being pivotally secured to the seat, a back pivoted to the seat, pivotal connections extending through the slots and 55 into the back, and means to hold the back and seat in parallel relation, the seat being designed to rest upon one of the connecting rods when in position for use as a chair.

3. A combination ironing board and chair 60 including a supporting structure comprising cross pieces, a rod connecting the cross pieces, a second rod connecting opposite arms of the cross pieces, angular extensions 65 formed on one set of arms of the cross pieces, said angular extensions being provided with arcuate slots, arms pivoted to the last mentioned connecting rods, a seat pivoted to the ends of the arms, a back pivoted to the seat, and pins extending through the slots and 70 into the back to pivotally and slidably hold the back in place.

In testimony whereof I affix my signature in presence of two witnesses.

OSCAR C. NELSON.
